CLAIM

The ornamental design for a radiator grille of car, as shown and described.

DESCRIPTION

FIG. 1 is a perspective view of new design for a radiator grille of car as shown in the drawings;

FIG. 2 is a front elevation view of the radiator grille of car;

FIG. 3 is a rear elevation view of the radiator grille of car;

FIG. 4 is a left side view of the radiator grille of car;

FIG. 5 is a right side view of the radiator grille of car;

FIG. 6 is a top plan view of the radiator grille of car; and,

FIG. 7 is a bottom plan view of the radiator grille of car.

1 Claim, 7 Drawing Sheets(56)
